(57) **CLAIM**

The ornamental design for a front cowl for a motorcycle, as shown and described.

DESCRIPTION

FIG. 1 is a perspective view from the left side of a front cowl for a motorcycle.

FIG. 2 is a perspective view from the left side thereof.

FIG. 3 is a perspective view from the right side thereof.

FIG. 4 is a perspective view from the right side thereof.

FIG. 5 is a front elevation view thereof.

FIG. 6 is a rear elevation view thereof.

FIG. 7 is a left side elevation view thereof.

FIG. 8 is a right side elevation view thereof.

FIG. 9 is a top plan view thereof.

FIG. 10 is a bottom plan view thereof; and,

FIG. 11 is a referential view showing use thereof.

The broken lines showing round and oval openings in FIGS. 1, 2, 3, 4, 5, 7, 8, 9 and 11 are boundary lines and form no part of the claimed design. The other broken lines showing portions of the front cowl for a motorcycle are for the purpose of showing environmental structure only and form no part of the claimed design.
